[57] CLAIM

The ornamental design for a plastic covered license plate frame, as shown and described.

DESCRIPTION

FIG. 1 is a front elevation view of a plastic covered license plate frame showing my new design;

FIG. 2 is a right side elevation view, the left side elevation view being the mirror image thereof;

FIG. 3 is a top plan view, the bottom plan view being the same;

FIG. 4 is an enlarged sectional view along the line 4—4 of FIG. 1; and,

FIG. 5 is a rear elevation view thereof.
